Patented Nov. 9, 1965

202,790

COMBINED TABLE AND MULTIPLE STUDENT BOOTH UNIT

Anthony D. Glover, P.O. Box 4093, Austin, Tex.

Original design application Oct. 26, 1962, Ser. No. 72,272,
now Design Patent No. 201,137, dated May 18, 1965.
Divided and this application Oct. 30, 1964, Ser. No.
82,390

Term of patent 14 years

(Cl. D33—11)

Fig. 1.

Fig. 2.

Fig. 3.Fig. 4.

FIG. 1 is a front perspective view of a combined table and multiple student booth unit embodying the design;

FIG. 2 is a view similar to FIG. 1 but showing the Instruction Table in position for phonetic instruction;

FIGURE 3 is a side perspective view showing the end not disclosed in FIGURE 2, and wherein the side not shown is like the side shown.

FIG. 4 is a side perspective view of the Instruction Table in the form of FIG. 1.

This application is a division of my application Serial Number D. 72,272 filed October 26, 1962, and now Design Patent Number D. 201,137.

I claim:

The ornamental design for a combined table and multi-

ple student booth unit, substantially as shown and described.
